ELECTRIC CIRCUIT CONTROLLING DEVICE

John D. Noyes, Detroit, Mich.

Application February 3, 1936, Serial No. 62,115

2 Claims. (Cl. 200—151)

The present invention relates to electrical circuit making and breaking devices and relates more specifically to devices taking the place of and of greater efficiency and convenience than the ordinary pothead.

Among the objects of the invention is a high voltage cable connection device in which all live parts are shielded at all times against accidental touching.

Another object is a device of the kind indicated in which all the working parts are enclosed in a water-tight casing with operating means extending to the outside thereof.

Another object is a device of the kind indicated which may be assembled completely and put in place before making or breaking any circuits.

Another object is a device of the kind described which is of relatively small size and therefore more conveniently installed and operated in the somewhat restricted spaces in which such devices are usually used.

Still other objects and advantages will be apparent to those skilled in the art upon reference to the following description and the accompanying drawings in which

Figure 1 is a longitudinal vertical section through a three element connector, it being understood that a smaller or greater number may be used.

Figure 2 is a vertical section on line 2—2 of Figure 1.

Figure 3 is a horizontal section on line 3—3 of Figure 1.

Figures 4 and 5 are diagrammatic illustrations of modified forms of the device.

Referring now particularly to Figures 1 to 3 of the drawings, a preferred form of embodiment of the invention will be seen to comprise a casing 10 capable of being tightly sealed by means of suitable flanges and bolts or screws 11. This casing 10, in the form shown, has its upper portion divided into four compartments by sheets or plates of insulating material 12 which also line the front and end walls of the casing. Three of the compartments of substantially the same size occupy the front portion of the casing while the fourth extends along the back, the compartments being separated from each other by the plates 12.

The top 13 of the casing is also lined with a plate or plates of insulating material 14 having a small opening 15 centrally located over each of the three front compartments and mounted upon the top 13 over each opening 15 is a bell member or casing extension 16 secured to the

top by any suitable means. These members 16 also are lined for a portion of their length with insulating material 17 as shown. Further, these bell members 16 are preferably provided with removable upper ends or caps 18 through which extend the ends of conducting cables or wires 19, means being provided to render the joints sufficiently tight to prevent entrance of water. The means shown is a screw nipple 20 to which the cable armor is secured as by a lead burned joint 21.

Within each bell 16, and supported by a suitable means such as a flange 22, is an insulated blade-carrying contact 23, the lower end carrying the blades 24, being placed above but in line 15 with an opening 15, and the upper end provided with means for making a suitable permanent connection with cable 19. The insulator for contact 23 is shown at 25.

Mounted within the rear compartment of casing 10 are fixed contact members 30 carried in suitable insulators 31 and having blades 32 extended forwardly through insulation 12, each into one of the front compartments in substantial alignment with an opening 15, but below 25 and to the rear of such opening. Each of the members 30, by means of a suitable plate 32a is connected to a tap lead wire or cable 33 leading from one of the main leads or conductors 34 extending lengthwise of the casing in the lower 30 part of the rear compartment, a suitable trough therefor being indicated at 35.

At each end of casing 10 opposite the trough is a flanged tubulated opening 40, this serving to admit the armored end of the (in this form) 35 three-wire main cable 41 containing the conductors 34, and providing means for the formation of a water-tight joint in the leaded flange 42, the latter being bolted or screwed to the casing flange.

The mains 34 may and ordinarily will continue through the casing 10, being tapped as mentioned above, and supply current to each of the members 30.

The conductors 19 of course extend to whatever circuits the device is intended to supply and means is provided within the casing 10 for establishing a connection between blades 32 and blades 24.

This latter means comprises in the preferred 50 form an insulating block member 50 carrying a T-shaped conductor blade 51 of which one end of the cross bar 51a is embedded or otherwise secured in block 50 while the stem 53 of the T extends toward the rear and is provided with an 55

insulating shield or barrier member 52. This T-shaped member is so placed on block 50 and is of such dimension that, when stem 53 is between the blades 32, the upper end of 51 is between blades 24.

The blocks 50 are preferably extended laterally and contain openings to receive the guide rods 60 upon which the blocks slide and are maintained in alinement with the blades 24 and 32. These rods 60 are, as indicated, fixed to the bottom of the housing 10.

Means is also provided for moving the blocks 60 and T-shaped members without the necessity of opening housing 10. This means comprises a shaft 70 journaled in the ends of the housing and extending from one end through a suitable gland 71 and provided with means such as a handle or lever 72 for rotation. This shaft 70 carries arms 73 fixed to it, each two arms extending to a block 59. Each arm has a slotted end or elongated eye 74 cooperating with a pin 75 in the block 59 so that movement of handle 72 raises blocks 50 to circuit-completing position or lowers them to circuit open position.

25 It will be noted that the contacts are brought together and separated behind ample barriers, the contacts 51 and 24 being made and broken within the domes 16 outside of the main housing, while contacts 53 and 32 are made and broken 30 behind the large barrier 52 with the conductors 33 outside of the insulated compartments.

It should be noted that while the preferred form of the device shows three taps, a greater or less number may be used without material 35 modification.

Figures 4 and 5 show diagrammatically somewhat modified forms of the invention.

In Figure 4 the casing 110, domes 118, and stationary contacts 124 and 132 may be similar in 40 construction to the corresponding parts of the preferred form and are shown more or less conventionally.

The circuit-completing member 151 is however shown as of U-shape with one leg 151a longer 45 than the other 151b, these coacting respectively with contacts 124 and 132. The member 151 is carried at the end of a swinging arm 173 pivoted or hinged at 173a, and having its ends separated by an intermediate insulator portion 173b. The 50 arm 173 is indicated as operable by means of a pump handle 172 mounted on the top of casing 110 and connected to arm 173 through links 170, one of which passes through a suitable packing gland 171. In this form, each member 151 may 55 have an operating handle or several may be operated by the same handle as in Figure 1. Suitable guides (not shown) will of course be provided.

Figure 5 is a diagrammatic showing of still 60 another form but in this the movable circuit completing member 251 remains in contact with

one of the stationary contacts 232 whether or not the end 233 contacts with the other stationary contact 224. In this form, the member 251 may be hollow with spring fingers 225 sliding upon contact 232 which is of considerable length and telescopes into member 251. Also in this form no guides are needed as the telescoping arrangement of parts 251 and 232 can be made of such form and proportions as to be sufficient for the purpose.

10 The member 251 is indicated as being operable through a suitable handle lever 272.

What I claim is:

1. A device of the character described comprising a sealed housing including a main casing, 15 insulating partitions in said casing dividing the space therein into at least two chambers, an extension casing removably affixed to the main casing and separated therefrom by an insulating member provided with a relatively small opening, 20 a stationary contact member mounted in one of said chambers and projecting through the partition into the other chamber, a stationary contact member mounted in said extension casing opposite said opening, a movable contact member 25 in said other chamber adapted to be moved into contact with the first stationary contact and project into said extension into contact with the second stationary contact, fixed baffle portions shielding each of said stationary contact members 30 and arranged at an angle to each other, and a movable baffle adapted to travel with said movable contact member into and out of abutting relation with respect to said first mentioned baffles, in a path between said baffles, and means 35 projecting from said casing for moving said movable contact member.

2. A device of the character described comprising a casing, an electrical conductor leading into said casing and sealed thereto at the point 40 of entry, a fixed contact member in said casing and connected with said conductor, an extension fixed to said casing in sealed relation and containing a second fixed contact member, a movable contact member in the casing having a portion 45 movable into contact with the first contact member and a portion projectable into said extension into contact with said second contact member, a baffle plate dividing said casing extension from the main casing and provided with 50 a relatively small opening for the passage of said projectable portion, a baffle carried by said movable contact member, and a fixed baffle shielding the fixed contact member in the casing, the baffle carried by said movable contact member being 55 movable into and out of abutting relation with at least one of said other baffles and means operable from without the casing for moving said movable member to and from contact making position.

60 JNO. D. NOYES.
